UNITED STATES PATENT OFFICE.

CHARLES A. MAXFIELD, OF NEW YORK, N. Y., ASSIGNOR TO JACOB WALLACE, TRUSTEE, OF SAME PLACE.

PRESERVING, STRENGTHENING, WATERPROOFING, AND GLOSSING TEXTILE FABRICS, INCLUDING PAPER.

SPECIFICATION forming part of Letters Patent No. 328,956, dated October 27, 1885.

Application filed May 23, 1885. Serial No. 166,496. (No specimens.)

To all whom it may concern:

Be it known that I, CHARLES A. MAXFIELD, a citizen of the United States, and a resident of New York, in the county of New York and 5 State of New York, have invented certain new and useful Improvements in Preserving, Strengthening, Waterproofing, and Glossing Textile Fabrics, including Paper, of which the following is a specification.

10 My present invention relates to preserving, strengthening, waterproofing, and glossing textile fabrics, including paper; and it consists in the application to one of the surfaces of such fabrics—preferably its exposed surface—of a coating of the natural wax known as “ozocerite.”

In my Patent No. 278,443, granted May 29, 1883, I described a new article of manufacture consisting of paper saturated or covered on 20 both surfaces with the natural wax known as “ozocerite.” For many uses—some of which are enumerated in said patent—this is a desirable commodity; but for other uses it has practically no value. Besides, paper or other 25 material treated as proposed in this application costs less than the same material which is treated by being saturated or covered on both surfaces, and in cases where nothing is to be gained by saturating or covering both 30 surfaces the present plan would obviously supersede the other.

I have treated wall-papers in the manner now described, so as to render them impervious to water, and thus enable them to be washed 35 the same as a painted surface. By the application of the ozocerite to wall-papers their colors are set, so that they not only do not rub off, but all liability of their affecting the health of persons—which sometimes happens where 40 the cheaper grades of papers are used—is counteracted. The surface of wall-papers thus treated may be glazed or not, according to the requirements of the trade. If an unglazed surface is desired, it is only necessary to apply a 45 low degree of heat to the unprepared surface of the paper, after having applied the ozocerite to its other surface. It is obvious that if wall-papers were saturated or covered on both 50 surfaces it would be practically impossible to make them adhere to the walls by the use of

the paste ordinarily employed for such purpose; besides, the cost of treatment of the paper would be largely increased.

Wall-papers treated in the manner now proposed would be quite indestructible, and the 55 cheaper grades of paper would be almost as desirable as the finer qualities.

My invention may also be used in the manufacture of pictures printed in colors—such as chromos and chromo-lithographs—the ozocerite in such cases serving to preserve the surface of the picture and rendering it capable of being washed without detrimentally affecting it.

I contemplate preparing paper of all descriptions in the manner herein explained—as, for instance, paper designed for use in various mercantile pursuits, such as the confectionery, dry-goods, fancy goods, and hardware branches of trade, and also paper to be used 60 for building and roofing purposes.

The qualities of ozocerite are such that paper prepared therewith in the manner explained will not impart to the article enclosed within it any discoloration or disagreeable odor.

Textile fabrics of various kinds may be rendered water-proof when treated as herein explained, and when thus prepared they may be used as substitutes for rubber water-proof 70 goods and made up into garments for various uses.

In carrying out my invention I may use any suitable machinery; but I prefer to employ the apparatus and method which form the subjects of applications for patents filed by me of even date with this application. In the applications referred to I have fully described a mode of preparing the paper or other fabrics. So far as this patent is concerned, it is sufficient if I state that the ozocerite may be applied to the paper, cloth, or other material by a hand-brush; but this process would be tedious and expensive.

The best method of applying the ozocerite 95 that I am now aware of is set forth in the applications above mentioned, and to which reference is here made for an explicit description thereof.

Having thus described my invention, what I 100

claim as new, and desire to secure by Letters Patent, is—

1. As a new article of manufacture, textile fabrics, including paper, having applied to one surface only thereof the natural wax known as "ozocerite," whereby said fabrics are strengthened, &c., and their said surface rendered water-repellent, substantially as set forth.

2. As a new article of manufacture, wall-paper having its face or exposed surface treat-

ed with the natural wax known as "ozocerite," substantially as and for the purpose set forth.

Signed at New York, in the county of New York and State of New York, this 19th day ¹⁵ of May, A. D. 1885.

CHARLES A. MAXFIELD.
